Inventor,

William Alexander Rowe.

UNITED STATES PATENT OFFICE.

WILLIAM ALEXANDER ROWE, OF GLOUCESTER, MASSACHUSETTS.

CERVIX-CLAMP FOR USE IN DENTISTRY.

No. 802,408.

Specification of Letters Patent.

Patented Oct. 24, 1905.

Application filed August 27, 1904. Serial No. 222,477.

To all whom it may concern:

Be it known that I, WILLIAM ALEXANDER ROWE, a citizen of the United States, residing at Gloucester, in the county of Essex and State of Massachusetts, have invented a new and useful Cervix-Clamp for Use in Dentistry, of which the following is a specification.

My invention is a cervix-clamp for use in dentistry, the objects of which are, first, to push the gum away from the tooth operated upon, either up or down, as may be required, after the rubber dam has been applied, thus exposing the cavity and keeping it dry during the operation. I attain these objects by the mechanism illustrated in the accompanying drawings, in which—

Figure 1 is an isometric view of the complete instrument. Fig. 2 is a side view of the instrument minus the arms, showing the corrugated union in section. Fig. 3 is a front view of the instrument minus the arms, showing the corrugated union in section, as in Fig. 2. Fig. 4 is a front view of one of the two arms forming a portion of the instrument and shows the adjusting-nut in place, also the projection near the end of the hook made use of to keep the arms in close contact with the tooth. Fig. 5 is a side view of the arm described under Fig. 4 and shows all details, as before described, also the slot in which the bar plays and upon which bar the adjusting-nut rests during the operation. Fig. 6 is a cross-section of the nut and arm on line E F. Fig. 7 is a top view of the instrument minus the arms and shows the bar referred to under Figs. 5 and 6, also the bar-support and the upper plate. Fig. 8 is a cross-section on line A B, the shaded portion indicating the corrugated union. Fig. 9 is a cross-section on line C D and shows a top view of the bottom plate together with a shaded cross-section of the lower screw.

Similar letters refer to similar parts throughout the several views.

The top plate *a* is supported upon the upper right screw *c*, said upper plate being covered by a layer of pliable rubber *b*, which rubber comes in direct contact with the cutting edge of the tooth which is pressed against it during the operation.

The bar-support *g* consists of a flat shelf projecting at a right angle with the upper right screw *c* and bearing near its outer end the bar *h*, against which the operating-nuts *k k* upon the arms *i i* are forced while the instrument is in use.

The lower left screw *d* rests upon the lower plate *e* and is joined to and operated in conjunction with the upper right screw *c* by the corrugated union *j*. The union *j* is operated 60 by a slight movement of the fingers, being turned to the left or right that the screws *c* and *d* may be drawn together or forced apart, as the case may require.

The lower plate *e* supports the lower left 65 screw *d* and is covered upon its under side by a layer of pliable rubber *f*, which rubber comes in contact with the cutting edge of the teeth directly opposite those upon which the operation is to be performed.

The arms *i i* are supported by the burred nuts *k k*, which nuts press upon the bar *h*. These arms *i i* are made left and right, as shown in Fig. 1, and consist of a split screw-shaft threaded and curved to the left and right 75 and ending in a hook, near the end of which is a projection *l l*.

The projection *l l* enables the operator to keep the hook end of the curved portion of the arm firmly against the tooth upon which 80 the operation is to be performed.

The burred nuts *k k* play upon the threaded portion of the arms *i i* and rest upon or are forced against the bar *h*, the arms *i i* being raised or lowered by a turn of the burred 85 nuts *k k*.

The slot *m* in the threaded portion of the arms *i i* allows for the play of the arms *i i* upon the bar *h*.

What I claim as my invention, and desire to 90 secure by Letters Patent, is—

1. In combination, a mouth-prop, an extension on the prop, and adjustable means carried by the extension for engaging a tooth.

2. In combination, a mouth-prop, an extension thereon, and arms carried by the extension for engaging a tooth. 95

3. In combination, a mouth-prop, an extension thereon, a bar carried by the extension and split arms engaging the bar. 100

4. In combination, a mouth-prop, an extension thereon, a bar carried by the extension, split arms engaging the bar, and means carried by the arms for regulating the movement of the arms of the bar in one direction. 105

5. In combination, a mouth-prop, an extension thereon, arms carried by the extension, and means carried by the arms for adjusting said arms with relation to the extension.

6. In combination, a mouth-prop, an extension thereon, and arms independent of each other carried by the extension. 110

7. In combination, a mouth-prop, an extension thereon, threaded arms carried by the extension, and nuts working on the arms and bearing on the extension for adjusting said arms.
- 5 8. In combination, a mouth-prop having an extension, a bar carried by the extension, split arms loosely engaging the bar and means for limiting the movement of the arms in one direction.
- 10 9. In combination, a mouth-prop, an extension thereon and arms carried by the extension, said arms having a curved end portion for engaging a tooth.
- 15 10. In combination, a mouth-prop, an extension thereon, arms carried by the extension, and a projection on each of the arms for engaging a tooth.
- 20 11. In combination, a mouth-prop, an extension thereon at right angles thereto, and means carried by the extension for engaging a tooth.
12. In combination, a mouth-prop, an extension thereon, arms carried by the extension, each of said arms having an end portion curved, and projections on the curved portions of the arms.
13. In combination, a mouth-prop, an extension thereon, arms carried by the extension, and means carried by the arms to engage a tooth.
14. In combination, a prop formed in sections, adjustable one with relation to the other, an extension carried by one of the sections, and arms carried by the extension.
- In testimony whereof I have signed my name to this specification in the presence of two subscribing witnesses.

WILLIAM ALEXANDER ROWE.
